UNITED STATES PATENT OFFICE.

CHESTORA C. CARR AND JOHN HENRY CARR, OF HILSDALE, MICHIGAN.

APPLIANCE FOR WOMEN'S WEAR.

SPECIFICATION forming part of Letters Patent No. 645,457, dated March 13, 1900.

Application filed May 26, 1899. Serial No. 718,441. (No model.)

To all whom it may concern:

Be it known that we, CHESTORA C. CARR and JOHN HENRY CARR, citizens of the United States, residing at Hillsdale, in the county of 5 Hillsdale and State of Michigan, have invented a new and useful Appliance for Women's Wear, of which the following is a specification.

This invention relates to a garment-supporting appliance for women; and it has, primarily, for its object the provision of a simple and inexpensive device having means for positively supporting a plurality of skirts to prevent sagging at the back, while at the 15 same time firmly holding the inner and outer waists of the wearer, so that the garments will maintain a correct position on the body and preserve the proper fit.

A further object of the invention is to associate the garment-supporting means with a harness for the body, whereby the harness will be held properly positioned by reason of the engagement of the skirts with the supporting device associated with the harness.

Broadly the device includes a member 25 adapted to be worn on the body, in combination with a garment, of a hook and eye, the respective parts of which are secured to said member and to said garment, and said hook 30 being adapted to receive one or more articles of apparel interposed between said two last-mentioned parts, which latter are secured therein by the eye, and to secure a more perfect union of the different parts we prefer to 35 employ two hooks and eyes.

In its aspect as a combination garment-supporting appliance the invention involves a novel construction of body-harness providing for the support of the abdomen and back, 40 as well as for providing for bracing the shoulders and supporting the hose.

With these ends in view the invention consists in the novel combination of elements and in the construction and arrangement of 45 parts, which will be hereinafter fully described and claimed.

To enable others to understand the invention, we have illustrated the preferred embodiment thereof in the accompanying drawings, forming a part of this specification, and in which—

Figure 1 is a front view of the complete ap-

pliance shown fitted to the body of a woman. Fig. 2 is a rear view thereof. Fig. 3 is a detail in perspective of the eyeleted body member with which the hooks of the supporting device are associated. Fig. 4 is a detail vertical sectional view showing the manner in which the supporting device is associated with the eyeleted body member to provide 60 for supporting a plurality of skirts and also holding down an outer waist. Fig. 5 is a cross-sectional view showing the engagement of the hook member in an eyelet of the body member. Figs. 6 and 7 are details in perspective, respectively, of the hook and eye.

Like characters denote like and corresponding parts in each of the several figures of the drawings.

The device as a combination garment-supporting appliance includes in its organization a body member which is adapted to be worn by the user and which is denoted by B, and it is represented as consisting of a harness which involves, preferably, in its construction an abdominal piece or supporter 2 of substantially-segmental shape connected by the flexible or elastic straps 3 with the part 4, which fits against the small of the back, and these may be made from any suitable material, and the parts 2 and 4 are provided with depending tabs 5, to which the ends of a catamenial bandage can be attached in the familiar manner.

The straps or suspenders 6 are fastened to 85 the abdominal supporter 2 and cross the front and pass over the shoulders and terminate at a point above the part 4, and the free ends of these straps are provided with eyelets 7 to receive the lacing-cord 8, by which the relative 90 position of the two straps where they fit against the back can be adjusted, and these straps carry the hooks by which the skirts are supported through the agency of eyes on said skirts adapted to engage the hooks, and the 95 different articles of apparel, such as outer and inner waists disposed between the skirt and the body, are held down by being folded or thrust into the hooks, being secured therein by the eyes.

The hooks to which reference has been made are denoted by 9 and the coöperating eye by 10, and each skirt is provided with two eyes, and all of these are preferably formed from

wire, and each is in one piece. It will be understood, therefore, that each hook receives two eyes.

The hooks have bends or **U**'s 12 at their lower ends and also vertical side legs or branches 13, which converge slightly upwardly and which are adapted to extend through transversely-alined eyelets 7 in the free ends of the body-straps 6, and the extremities of these branches are bent inward, as at 14, to hold the hooks against withdrawal, and these inwardly-bent portions are rounded, so as not to present any angles to the clothing to tear or otherwise injure the same. The bends 12 are bulged outward, thereby producing a shape that cannot tear and also constituting a guide over which the eyes can ride, so as to properly seat the same, and the inward projections 15 at the free ends of the bends produce a narrow throat at this point and serve as a means for securely holding the eyes therein against ordinary pressure due to play of the skirts while worn.

The eyes 10 are of substantially **U** shape and are made comparatively wide, so as to hold the article firmly in the hooks and prevent lateral or side motion of the same. The branches of the eyes are provided with smaller eyes at their free ends to receive stitching or to be secured in some other suitable manner to the skirts S and S' along the upper edge thereof.

By reason of the construction and arrangement of parts described it will be observed that the weight of the skirts which are supported by the hooks 9 will be transferred to the back-straps 6, and thereby serve to exert an upward strain upon the abdominal supporter 2 and the hose-supporting tapes or garters 20, which are attached to said abdominal supporter or piece. Hence the garment-supporting device consisting of the hooks and eyes is essential to provide for the attachment of the skirts to the back-straps 6, whereby the latter will be drawn downwardly and hold the harness in proper position upon the body without discomfort to the wearer.

Two waists are represented, the inner one being designated by W and the outer one by W', and these are firmly held down at the back by the hooks 9, the lower edges of the same being disposed between the outer skirt and the body and being folded or placed in the hooks and held therein by the eyes on the skirt or skirts.

The effect produced by the attachment described is neat and dressy, and the waists are

prevented from drawing up at the back, which is exceedingly annoying, and the skirt or skirts are sustained without any tendency to sag and are carried without undue effort by the wearer.

In disrobing the skirts are first unhooked, after which the waists can be released from the hooks and taken off, so as to permit the straps 6 to be removed over the head.

Changes in the form, proportion, size, and the minor details of construction within the scope of the appended claims may be resorted to without departing from the spirit or sacrificing any of the advantages of this invention.

Having thus described the invention, what is claimed as new, and desired to be secured by Letters Patent, is—

1. In a body appliance of the character described, the combination with a body member, comprising shoulder-straps having eyeleted ends arranged at the back of the wearer, of hooks and eyes, the respective parts of which are detachably secured to the eyeleted ends of said straps and to a garment, said hook being arranged to receive the folds of one or more articles of apparel, and the eye being adapted to engage with the folds within the hook, substantially as set forth. 75

2. In an appliance of the class described, the combination of the body-harness including an abdominal supporter, and garters, and provided with shoulder-straps having the free ends thereof arranged at the back of the wearer, and a garment-supporting device suspended from said free ends of the shoulder-straps, substantially as set forth. 85

3. In an appliance of the class described, the combination of a body-harness provided with shoulder-straps having eyeleted ends arranged at the back of the wearer, and a garment-supporting device having hooks detachably suspended from the eyeleted ends of said straps, substantially as set forth. 95

In testimony that we claim the foregoing as our own we have hereto affixed our signatures in the presence of witnesses.
